UNITED STATES PATENT OFFICE.

CHARLES H. MILES, OF CHICAGO, ILLINOIS.

PISTON-PACKING.

1,260,009.

Specification of Letters Patent. Patented Mar. 19, 1918.

Application filed October 5, 1915, Serial No. 54,118. Renewed November 10, 1917. Serial No. 201,406.

To all whom it may concern:

Be it known that I, CHARLES H. MILES, a citizen of the United States, residing at Chicago, in the county of Cook and State of Illinois, have invented certain new and useful Improvements in Piston-Packings, of which the following is a specification.

My invention relates to piston packing for internal combustion engine or steam pistons, and the object is to provide perfect expandable packing rings for pistons so that there can be no leaking of steam or of explosive force past the pistons and to provide continuous packing surfaces on the bottom and top edges and on the peripheries of the packing rings and thus close all possible places against the passage of steam or of explosive force. Other objects are to provide a packing ring which will be unitary in action, that is, which will operate as a single packing ring, for mounting and adjusting purposes but which is provided with expandable members. Other objects and advantages will be fully explained in the following description and the invention will be more particularly pointed out in the claims.

Reference is had to the accompanying drawings which form a part of this application.

30 Figure 1 is a perspective view of a packing ring assembled, being constructed as of one piece of metal. Fig. 2 is a similar view of the same inverted. Fig. 3 is a diametrical section, taken on the line $x-x$ of Fig. 1. Fig. 4 is a diametrical section, taken on the line $y-y$ of Fig. 1. Fig. 5 is a diametrical section, taken on the line $z-z$ of Fig. 1. Fig. 6 is a perspective view of the central member of the packing ring without the cooperative expansion members. Fig. 7 is a perspective view of one of the detached expandable members.

Similar characters of reference are used to indicate the same parts throughout the several views.

50 The improved packing ring is provided with a central member 1 which is an open ring, but provided with a lapped or stepped joint 2 so that this member can expand without breaking the continuous peripheral surface. Expandable members 4 and 3 are formed on the outside of the member 1 and constitute the packing members. The members 1, 3, and 4 may be formed separately, 55 as shown in Figs. 6 and 7, and then made rigid with each other for approximately

two thirds of the circle and this rigid part should be opposite the joint 2 of part 1, but each member 3 and 4 is rigid or integral with the member 1 approximately two thirds of the circle. The member 3 is attached by brazing or hard soldering to the part 5 of the joint 2 and to the part 1 on around to the right to the end of member 3, as shown in Fig. 1. This will strengthen 65 part 5 of member 1. The expansion member 4 is attached to the part 6 of joint 2 and to the part 1 on around to the left in Fig. 2 to the end of member 4. This will strengthen part 6 of member 1. Thus each 70 expansion member 3 and 4 is rigid with the inner expansion member 1 for approximately two thirds of the circle and both members 3 and 4 are rigid with the part of the member 1, as shown in Fig. 1. This 75 strengthens the member 1 at that portion of member 1 which is opposite the joint 2. The inner member 1 may be made of steel, as the periphery of this member never comes in contact with the piston cylinder, but 80 the members 3 and 4 should be made of gray iron. The packing ring can be made much stronger and more durable by making the inner member of spring steel and the ring will be more resilient.

85 With the construction shown, there is a continuous pressure surface on the periphery of the packing ring, a continuous pressure surface on the bottom edge and a continuous pressure surface on the top edge of 90 the ring, so that no oil, or steam, gas, or other element can pass at any point of the piston packing. The joints between the members are preferably ground joints so that 95 there can be no leaking. There is thus a double check against the passage of any element through the packing or behind the packing. When a piston goes down, there is a tendency to create a vacuum along the wall of the groove and oil would run in and 100 pass behind the packing. But with a double check, as, described, the oil cannot escape from above the packing because there is a continuous pressure surface against the upper wall of the groove in the piston. It 105 will be understood that the top edge of the member 1 and the top edge of member 3 are flush with each other and that the bottom edge of member 1 and the bottom edge of member 4 are flush with each other.

110 The members 3 and 4 may be of the same material as the member 1 and be made in-

tegral therewith, as shown by the full line drawings.

What I claim, is,—

1. A packing ring having a body ring member provided with an opening and a lapped joint closing said opening and open expansible ring members formed on the periphery of said body member and bridging said joint and each expansible member having one end free for approximately one third of the circle and the expansible members forming a continuous peripheral pressure surface.
2. A packing ring having a spring body ring member provided with an opening closed by a lapped joint and open expansible ring members formed on the periphery of said body member and bridging said joint and each expansible member having one end free for approximately one third of the circle and the free portion of one expansible member being diametrically opposite the free portion of the other expansible member and the expansible members forming a continuous peripheral pressure surface of the packing ring.
3. A packing ring having an expansible body ring member provided with an opening closed by a lapped joint and open expansible ring members bridging said joint and extending in opposite directions from said joint and brazed to the periphery of said body member for approximately two thirds of the circle and having the unbrazed portions thereof diametrically opposite each other and said expansible members forming a continuous peripheral packing surface.
4. A packing ring having an expansible body member provided with an opening closed by a lapped joint and open expansible members bridging said joint and brazed to

the periphery of said body member, one expansible member being brazed to one member of said lapped joint for approximately two thirds of the circle and each open expansible member having a free end approximately one third of the circle.

5. A packing ring having an open expansible inner ring member, and outer expansible ring members bridging the opening in said inner member and brazed to said inner member for approximately two thirds of the circle and having free ends diametrically opposite each other, one expansible member extending from the upper part of said joint free in one direction and the other expansible member extending from the lower part of said joint free in the other direction.

6. A packing ring having an inner open expansible ring member, and outer open expansible ring members bridging the opening in said inner member and extending in opposite directions from said joint and brazed to the periphery of the inner member for approximately two-thirds of the circle, said outer members having portions thereof free from said inner member and the free portion of one outer member being diametrically opposite the free portion of the other outer member.

7. A packing ring having an inner open spring steel ring member, and outer open expansible ring members of gray iron bridging the opening of said inner member and brazed to the periphery of said inner member and extending free in opposite directions from said opening and forming continuous packing surfaces on the edges and on the periphery of the packing ring.

In testimony whereof, I set my hand this 12th day of July, 1915.

CHARLES H. MILES.
